SUCTION CLEANER

Quentin Berg, Canton, Ohio, assignor to The Hoover Company, North Canton, Ohio, a corporation of Ohio

Application December 14, 1938, Serial No. 245,623

7 Claims. (Cl. 306—13)

The present invention relates to suction cleaners and particularly to a new and improved handle control mechanism in a suction cleaner. More specifically, the invention comprises an improved handle position control in a suction cleaner which is characterized in that the handle control mechanism is arranged above the body of the suction cleaner.

It is an object of the present invention to provide a new and improved suction cleaner. It is another object to provide new and improved handle controlling means in a suction cleaner. It is another object to provide a handle control which is hand operated to control the movement of the handle to different operative positions. Another object is to provide a handle control that is operated by a foot pedal arranged above the body of the suction cleaner. Further objects and advantages of the invention will be apparent upon referring to the following specification and claims, and the attached drawings, wherein:

Figure 1 is a side elevational view of a suction cleaner embodying the present invention;

Figure 2 is a broken elevational view partly in section showing one embodiment of the invention, the handle being arranged in storage position;

Figure 3 is a front sectional view of the embodiment shown in Figure 2;

Figure 4 is an enlarged perspective view of the locking detent means;

Figure 5 is a longitudinal section of another embodiment of the invention;

Figure 6 is a rear elevational view partly in section of the construction shown in Figure 5;

Figure 7 is a top plan view of the construction shown in Figure 5, and

Figure 8 is an exploded view of the parts constituting the foot operated handle control mechanism.

One embodiment of the invention is disclosed in Figures 1 to 4 and comprises a suction cleaner having a main casing 10 provided with a nozzle 11, and an unshown fan chamber communicating with an exhaust passageway 12. The rear of the exhaust passageway is provided with a vertical flange 13 to which is removably secured a dirt bag 14. The casing 10 supports an unshown motor enclosed in a motor housing 15, and the motor operates an unshown fan to create suction and draw dirt-laden air from the surface being cleaned, through the nozzle 11, into the unshown fan chamber and is discharged into the filtering bag 14. The cleaner is supported on front and rear wheels 16 and 17, respectively.

The cleaner is propelled over the surface covering being cleaned by means of a handle 18 pivotally mounted to the body of the cleaner through being removably clamped in a split socket 19 which is formed with integral side walls 20, 20 spaced apart by substantially the diameter of the handle and joined by a circular top wall 21 and a rear wall 9. The pivotal axis is formed by a pin 22 which extends through the side walls 20 of the handle socket and is carried by the side walls 23, 23 of a bracket 23 rigidly mounted upon the top surface of the exhaust outlet 12. The bracket 24 is of substantially U-shape and the opposed side walls 23 thereof are spaced apart by means of a connecting rear wall 25 which is suitably secured to the exhaust flange 13.

Segment means 29, 29 are formed integrally with the side walls 23 of the handle bracket 24 by forming thereon stops 26 and 27 which provide different ranges of handle movement.

Cooperating with the segments 29 is a latch or locking detent plate 30 pivotally mounted upon a pin 31 supported in the side walls of the handle socket. The detent plate 30 has its upper end doubled back on itself to provide a sleeve 32 which is arranged about the pivot pin 31, and the lower end of the detent plate is provided with transversely extending locking detents or pins 33, 33. The detent plate 30 is pivoted in the handle socket above the pivotal axis of the handle and extends downwardly from its pivotal axis 31 for engagement with the stops 26 to hold the handle in storage position, and is engageable with the surfaces 34 between the stops 26 and 27 to hold the handle in an intermediate operating range, and also rides on the surfaces 35 at the top of the segments 29 to permit movement of the handle in a low operating range. Movement of the handle to its lowest operating position is limited by engagement of the extreme lower end 36 of the handle socket rear wall 9 with the portions 47 on handle bracket 24. The handle is limited in its upward movement by engagement of the extreme end of the socket front wall 21 with the handle bracket 24, as best shown in Figure 2.

In order to normally urge the locking detents 33 into engagement with the segments 29, a spring 37 is interposed between the front wall 21 of the handle socket and the detent plate 30, the spring 37 being supported about a pin 38 mounted on the detent plate 30. A relatively strong spring 39 is disposed along one side of the handle and has one end connected to a pin 40 extending laterally from the handle socket 19 below the 55

pivotal axis 22 of the handle, and the other end of the spring is connected to a lug 41 formed on the cleaner casing 10. The spring 37 is so arranged below the pivotal axis of the handle to at all times exert a force to move the handle upwardly to counter-balance the handle weight.

A hand operated mechanism is provided to operate the detent member 38 and comprises a plate 43, its lower end being adapted to engage a cam 44 which is struck out of the detent member 38, the actuating plate 43 being provided with an elongated opening 45 whereby the plate 43 is slidably mounted with respect to an electric plug 46 having a portion extending through the opening 45 for attachment to the handle socket 19. The spring 37 urges the plate 43 into engagement with the lower end of a rod 48 of channel configuration which extends upwardly through the handle 18 along the rear wall of the latter. A rod 50 is attached to the upper end of the rod 48 and extends into a hand grip 51 and is connected to a lever 52 pivotally mounted at 53 in the hand grip 51. A push button 54 is disposed in the side wall of the hand grip 51 and loosely receives one end of the lever 52, whereby upon exerting pressure on the button 54 the rods 50 and 48 and plate 43 are moved downwardly in the handle to actuate the detent plate 38 to permit movement of the handle to any operative position.

The hand grip 51 is formed of insulating material and comprises a top wall 55 and a pair of opposed side walls 56 which define a recess 57 for receiving the hand operated mechanism.

A plurality of transverse ribs 58 are arranged in the recess 57 of the hand grip and are provided with slots 59 for the slidable reception of the rod 50. A cover or bottom plate 60 is removably secured by means of screws 61 to the body of the hand grip 51. Disposed in the hand grip 51 is a switch 62 for controlling the supply of current through the conductors to the unshown motor. A hook 63 is anchored to the cover plate 60 to support the upper end of the cleaner bag 14.

In operation, assume the handle 18 is in storage position, the locking detents 33 will then be held in engagement with the stops 28 by the spring 37. In order to lower the handle to a convenient operating angle the operator places his hand in the usual manner about the hand grip 51 and moves the plunger 54 into the hand grip 51 which causes the lever 52 to rotate on its axis 53 and the rods 50 and 48 and plate 43 to move downwardly in the handle, the plate 43 engaging the detent plate 38 to pivot it about its axis 31 thus moving the locking detents 33 out of engagement with the stops 28 whereby the handle can then be pivoted downwardly into the working range between the stops 28 and 27. The operator then releases the button 54 and the latch spring 37 rotates the detent plate 38 counter-clockwise as viewed in Figure 2, causing the hand operated mechanism to move upwardly in the handle 18 and the push button 54 to its normal position. At the same time the latch spring 37 urges the locking detents 33 into sliding engagement with the surfaces 34 between the stops 26 and 27. If the operator desires to use the handle in a lower position, the push button 54 is operated to actuate the latch plate 38 which moves the locking detents 33 out of engagement with the stops 27, whereby the push button 54 may then be released and the handle pivoted downwardly permitting the locking detents 33 to slide upon the surfaces 35, the handle be-

ing limited in its downward movement by engagement with the stops 47 on the handle bracket. Should the operator desire to return the handle to a higher operating range or to storage position, he merely pivots the handle upwardly and the locking detents 33 will ride over the cam surfaces 34 and 35 by forcing the detent plate 38 to move against the force of the latch spring 37, without requiring the operator to manipulate the push button 54.

Another embodiment of the invention is shown in Figures 5 to 8 and comprises the handle 18 disposed in the handle socket 19 pivotally supported upon the pivot pin 22 supported in the spaced arms 23 of the bracket 24 which is rigidly secured to the cleaner body 10 on the top of the exhaust passageway 12. Formed integrally with the bracket 24 are the segments 26, 27 and 28 provided with the stops 26, 27 and 28 defining therebetween different operating ranges of movement for the handle 18.

Cooperating with the segments 29 is a latch plate 70 provided at its upper end with an integral sleeve 71 pivotally mounted on a pin 69 rigidly secured to the handle socket 19 above the pivotal axis 22 of the cleaner handle 18. The detent plate 70 is provided with laterally projecting locking detents 72 for engagement with the stops 26, 27 and 28 on the segments 29 to position the handle in different operating positions. The locking detents 72 are at all times urged into engagement with the segments 29 by means of a spring 73 bearing against the handle socket wall 21 and arranged about a pin 74 secured to the latch plate 70.

In order to actuate the latch plate 70 with respect to the segments 29 a foot operated lever 75 is provided and comprises an elongated lever arm 76 terminating in a laterally extending pedal 77 which is adapted to receive the foot of the operator. The lever 75 is also provided with an offset portion having spaced members 68, 69 between which an actuating lever arm 78 extends upwardly and is provided with an opening 79 in which is disposed the pivot pin 22, the opening 79 being considerably larger than the pivot pin 22. The lever 75 is pivotally supported by means of a pin 80 extending through the members 68, one end of the pin being supported in the back wall 25 of the handle bracket 24 and the other end supported in a plate 81 rigidly secured to one of the side walls 23 of the handle supporting bracket 24. A coil spring 82 is arranged about the pivot pin 22 and between the actuating lever arm 78 and one of the side walls 23 of the handle bracket 24 and tends at all times to pivot the lever 75 counter-clockwise as viewed in Figure 8, about the pivot pin 22 to urge the foot pedal 77 upwardly into handle locking position. The lever arm 76 of the lever 75 is provided with a cam surface 84 which is adapted to engage a cam surface 85 on a cam 86 rigidly secured to the detent plate 70 to disengage the locking detents 72 from the segments 29 when the foot pedal 77 is depressed. The lever 75 is completely arranged above the cleaner casing 10 to provide a convenient location for the foot pedal 77 that is easily contacted by the foot of the operator. The motor housing 15 is provided with a slot as shown in Figure 8, along its marginal edge to accommodate the lever arm 76 extending exteriorly of the motor housing.

A relative strong spring 87 has one end secured to a pin 88 rigidly attached to a side wall 29 of the handle socket and has its other 75

end attached to a lug 89 formed in the main casing 10. The spring 87 is arranged below the pivotal axis 22 of the handle and at all times tends to counter-balance the weight of the cleaner handle 18.

In operation, assume the handle 18 to be in storage position, the locking detents 72 being urged into engagement with the stops 26 on the segments 29 by means of the latch spring 73. In order to lower the handle to a convenient operating angle, the operator steps upon the foot pedal 71 thereby pivoting the lever 75 about the pin 80 against the force exerted by the coil spring 83 and causing the lever arm 78 to move to the right as viewed in Figure 8, against the force of the spring 83. Movement of the lever arm 78 with respect to the pivot pin 22 is permitted due to the relatively large diameter of the opening 79 with respect to the pivot pin 22. This movement of the lever arm 78 causes it to engage the cam surface 85 on the cam 86 to pivot the latch plate 10 about its pivot pin 69 in a clockwise direction, as viewed in Figure 8, to withdraw the locking detents 72 from engagement with the stops 26, the handle can then be pivoted downwardly into the working range between the stops 26 and 27. The operator then removes his foot from the pedal 71 whereby the coil spring 83 pivots the lever 75 about its axis 80 in a counter-clockwise direction, as viewed in Figure 8, causing the lever arm 78 to move out of engagement with cam 85 permitting the locking detents 72 to ride upon the surfaces 34 between the stops 26 and 27. If the operator desires to use the handle in a lower operating position, the foot pedal 71 is depressed to move the lever arm 78 into engagement with the cam 85 on the latch plate 10 causing the latter to move out of engagement with the stops 27, whereby the handle 18 may be pivoted downwardly at which time the operator removes his foot from the pedal 71 and the locking detents 72 enter the working range between the stops 27 and 28. Should the operator desire to return the handle to a higher operating range or to storage position, he merely pivots the handle upwardly and the locking detents 72 ride over the cammed surfaces 34 and 35 forcing the latch plate 10 to pivot against the force of the latch spring 73 without the necessity of manipulating the foot pedal 71.

From the foregoing, it will be perceived that in both embodiments of the invention the segments and the latch mechanism are completely enclosed within the handle socket, that the motor housing 15 extends rearwardly to enclose the pivots of the handle, and that in the second embodiment the foot operated lever is arranged at the top of the cleaner casing 10 above the exhaust passageway 12.

It is to be understood that the protection herein applied for is not confined to the particular combinations of features or elements set out in the following claims. Protection is herein applied for, for any one or more of the features or elements referred to in the following claims, or described in the foregoing specifications or shown in the accompanying drawings, either independently or in combination.

I claim:

1. In a suction cleaner, a body, handle supporting means mounted on said body, a tubular handle pivoted on said handle supporting means, a pair of spaced locking segments integral with said handle supporting means and arranged with in said tubular handle, a latch member pivoted

in said tubular handle above the pivotal axis of the latter, a pair of locking detents integral with said latch member for engagement with said pair of locking segments, means in said tubular handle for urging said locking detents into engagement with said segments, and means for moving said latch member out of engagement with said locking segments to position said tubular handle in different operative positions. 5

2. In a suction cleaner, a body, a bailless tubular handle pivoted on said body, locking segment means mounted on said body, locking detent means pivoted in said tubular handle above the pivotal axis of the latter for engagement with the segment means to lock said tubular 10 handle in different operating positions, and hand operated handle controlling means comprising an abutment integral with said detent means, rod means slidably mounted in said tubular handle and extending from said abutment to the 15 upper end of said handle, lever means in said handle connected to said rod means, and means connected to said lever means adapted to be operated by the hand of the operator for effecting movement of said rod means to abut said 20 abutment and move said detent means out of engagement with said segment means. 25

3. In a suction cleaner, a body, a pair of spaced handle supporting members mounted on said body and upstanding therefrom, a bailless handle having a tubular portion enclosing said spaced members and pivotally mounted on the latter, segment means formed integrally on said spaced members and disposed within the tubular portion of said handle, a latch member pivoted in 30 opposed walls of the tubular portion of said handle, a pair of detents formed integrally with said latch member and engageable with said spaced segment means, a spring interposed between a 35 wall of the tubular portion of said handle and said latch member to urge said detents into engagement with said spaced segment means, and means for actuating said detents out of engagement with said spaced segment means to position 40 said handle in different operating positions with 45 respect to said body.

4. In a suction cleaner, a body, a pair of spaced handle supporting members mounted on said body and upstanding therefrom, a bailless handle having a tubular portion enclosing said spaced 50 members and pivotally mounted on the latter, segment means formed integrally on said spaced members and disposed within the tubular portion of said handle, a latch member pivoted in 55 opposed walls of the tubular portion of said handle, a pair of detents formed integrally with said latch member and engageable with said spaced segment means, a spring interposed between a 60 wall of the tubular portion of said handle and said latch member to urge said detents into engagement with said spaced segment means, and hand operated handle controlling means extending longitudinally through said handle for actuating said latch member to move said detents 65 out of engagement with said spaced segment means to position said handle in different operating positions with respect to said body.

5. In a suction cleaner, a body, handle supporting means mounted on said body, a bailless tubular handle pivotally mounted on said supporting means, segment means integral with said handle supporting means and enclosed within said bailless tubular handle, detent means pivotally mounted on said bailless tubular handle and enclosed within the latter, hand operated 70 75

handle control means comprising rod means slidably mounted in said bailess tubular handle and extending from said detent means to the upper end of said handle, lever means in said handle and connected to said rod means, and hand actuated means connected to said lever means for effecting movement of said rod means to move said detent means out of engagement with said segment means to position said handle in different operating positions.

6. In a suction cleaner, a body, a motor in said body, a tubular handle pivoted on said body, an electrical connector in said tubular handle for supplying current to said motor, cooperating handle locking means including segment and detent means mounted on said body and handle, handle control means including rod means slidably mounted in said tubular handle and extending from said locking means to the upper end of said handle, said rod means having an elongated opening accommodating said electrical connector, said elongated opening permitting movement of said rod means with respect to said

electrical connector, and hand actuated means connected to said rod means for effecting movement of the latter to actuate said locking means for movement of said handle to different operating positions.

7. In a suction cleaner, a body, a handle pivotally mounted on said body, segment means mounted on said body, latch means pivotally carried by said handle and engageable with said segment means for holding the handle in adjusted 10 position, rod means disjointed from said latch means and extending upwardly in said handle, hand actuated means connected to said rod means to operate the latter to move said latch means out of engagement with said segment 15 means, and a spring for moving said latch means into locking engagement with said segment means, said spring moving said rod means and hand actuated means into handle locking position upon said movement of said latch means 20 into locking engagement with said segment means.

QUENTIN BERG.

DISCLAIMER

2,218,161.—*Quentin Berg, Canton, Ohio.* SUCTION CLEANER. Patent dated October 15, 1940. Disclaimer filed January 27, 1941, by the inventor; the assignee, *The Hoover Company*, consenting.

Hereby disclaims from the scope of claim 2 of said patent any suction cleaner in which the pivotal axis of the locking detent means is not above the pivotal axis of the handle in all operating positions of the handle, and hereby disclaims claim 7.
[Official Gazette February 18, 1941.]
